Mass., a voluntary association of Massachu-
sets

Application January 15, 1936, Serial No. 59,247

14 Claims. (Cl. 88—47)

This invention relates to improvements in ophthalmic mountings and has particular reference to improved lens holding means and method of making the same.

5 This application is a continuation in part of my co-pending application Serial No. 744,917 filed September 21, 1934.

One of the principal objects of the invention is to provide an improved lens holding means that 10 will resiliently ease off the rigidity in the connection of the holding means to the lens, that will insure the said holding means returning to its initial aligned position after such easing off, that will provide means for controlling the tension of the resilient means during use, that will maintain the connection of the holding means to the lens firm and substantially rigid to prevent looseness and play during the use of the mounting and yet be of such a nature as to relieve 20 shocks and strain on the lenses when the glasses are dropped or roughly handled and that will eliminate the exactness and accurateness in the fitting of the parts to be connected usually required in mountings of this character in the past.

25 Another object of the invention is to provide resilient means of the above character having a plurality of overlying sections, each of which forms a resilient backing support for the adjacent section, and each of which may be of equal 30 or varied resiliency, as desired.

Another object is to provide novel means and method of forming the resilient means and of attaching said resilient means to the lens holding means whereby the opposite ends of the 35 resilient means will exert forces on the lens holding means acting substantially in equilibrium about the connection of the lens holding means to the lens.

Another object is to provide lens holding means 40 of the above character so constructed that the tension of the resilient means may be varied as desired.

Another object is to provide a relatively narrow attachment for the resilient means to the 45 lens holding means in the direction of the edge of the lens whereby the conventional rigid backing shoe usual in prior art structures of this nature is eliminated and the normal pivotal action of the lens holding means on the lens will be greatly increased.

Another object is to provide the backing for 50 the resilient means on the lens holding means with relatively straight transversely extending upper and lower edge portions whereby the said

edge portions will have substantially line contact with said resilient means when they are flexed.

Another object is to provide the resilient means with relatively straight transversely extending end portions whereby the said resilient means 5 will have substantially line contact with each other and with the lens at their respective ends.

Another object is to provide novel means functioning separately of the lens face engaging portions of the lens holding means for attaching the 10 resilient means to said lens holding means and for preventing twisting of said resilient means sidewise relative to said lens holding means during use.

Another object is to provide the resilient means 15 nearest the lens with cylindrical shaped end contacts with the edge of the lens whereby a substantial line contact transversely of said edge will exist at different positions of flexing of the resilient means.

Another object is to provide a novel arrangement whereby the resilient means is spot welded 20 to the lens holding means.

Another object is to provide novel means and method of making lens holding means of the 25 above character.

Other objects and advantages of the invention will become apparent from the following description taken in connection with the accompanying drawing, and it will be understood that many 30 changes may be made in the arrangement of parts, details of construction and methods shown and described without departing from the spirit of the invention as set forth in the accompanying claims. I, therefore, do not wish to be limited 35 to the exact arrangement of parts, details of construction and methods shown and described as the preferred forms only have been shown by way of illustration.

Referring to the drawing:

Fig. I is a fragmentary front elevation of an ophthalmic mounting embodying the invention and showing low position straps or lens holding means;

Fig. II is an enlarged fragmentary perspective 45 view of the strap or lens holding means of Fig. I;

Fig. III is a sectional view of said lens strap or holding means;

Fig. IV is a sectional view taken as on line IV—IV of Fig. III;

Fig. V is a sectional view taken on line V—V of Fig. IV;

Fig. VI is a view similar to Fig. III showing a modified form of strap or lens holding means;

Fig. VII is a view similar to Fig. V showing a 55

modified form of spring connecting means and support;

Fig. VIII is a sectional view taken on line VIII—VIII of Fig. VI, and

5 Fig. IX is a view similar to Fig. VI showing another modified form of the invention.

Much difficulty has been encountered in the past in fitting and securing the lens straps or holding means of rimless type ophthalmic mountings to the lenses so that the said lens holding means will have relatively free resilient action and yet be prevented from becoming loose and wabbly during use. One of the difficulties has been that, in most instances in the past, the 10 means employed for resiliently taking up the looseness and play of the lens holding means on the lens depended upon the support of a rigid backing shoe and, due to the restricted size of such devices, were not sufficiently durable to 15 produce the most desirable structure, that is, the resiliency of the resilient means would soon play out or the solid backing shoe supporting said resilient means would become bent or distorted and permit the parts to loosen and move out 20 of aligned relation with each other during use. This was due primarily to the fact that, in most instances, the rigid backing shoe, in order to function properly, had to be fitted with the resilient means so that it would impart a crimping 25 action adjacent the opposite ends thereof when the lens holding means was moved on the lens. This crimping action was adapted to cause the straightening of the resilient means, after such flexing, to return the parts to their initial aligned 30 relation with each other. It is quite apparent that if the rigid backing shoe became bent during use, the device would not function properly.

It, therefore, is one of the primary objects of this invention to obviate the above defects by 40 eliminating the usual rigid backing shoe of lens holding means of this character, and to replace said backing shoe with resilient backing means which will allow the lens holding means a greater pivotal movement on the lens and provide freer 45 acting and more durable shock absorbing cushioning means.

A further object is to increase the normal resiliency easing off action of the resilient means and to increase the tendency of said resilient 50 means to return the parts to their initial set after such easing off.

Another feature is that of providing a novel method of forming and attaching the resilient means to their supporting means so that the said 55 resilient means will not become distorted during said attaching.

A further object is to provide a freer and wider range of flexing than has been usual in the past in devices of this character.

60 Referring more particularly to the drawing wherein like characters of reference designate like parts throughout the several views, the improved holding means or strap 1 embodying the invention, as shown in Figures I to III inclusive, comprises a portion 2, which when viewed from the front is relatively straight, and has a temple connection 3 adjacent one end thereof and a bifurcated portion 4 adjacent its opposite end. The bifurcations of the portion 4 are adapted to 65 engage with the front and rear surfaces of the lens 5 and are provided with openings aligned with an opening in the lens through which attaching means 7, such as a screw or other suitable means known to the art, is extended.

70 75 The lens holding means 1 is provided with re-

siliency means 8 formed of a plurality of sections 9, 10 and 11 of varying lengths which extend outwardly of both sides of said holding means and provide relatively long free action resilient means having no backing shoe in engagement with the rear thereof for limiting their movement. The lens holding means 1 is attached to the lens by the connecting means 7. The resilient sections 9, 10, and 11, are provided with aligned attaching openings through which a rectangular 10 projection 12 at the base of the bifurcation of the lens holding means extends and which is headed over to secure the sections to said base. The different sections may be varied in resiliency or may be of the same resiliency, as desired, with 15 the section 9 more rigid than the section 10 and the section 10 more rigid than the section 11. The lens holding means in this instance is of such a nature that it may be moved upwardly and downwardly in the plane of the lens about the 20 connecting means 7 as a center and provides free action shock and strain absorbing means in both directions. The resilient means 15 in this instance also takes up the looseness and play of the connecting means and also acts as shock absorbing 25 means. It also tends to maintain the lens holding means in proper aligned relation with the lens, that is, if deflected upwardly or downwardly about the connecting means 7, it will always tend to return to its initial set. 30

The base of the bifurcation in the rear of the resilient sections 9, 10 and 11 and to which the said resilient means is attached by the projection 12 is relatively narrow in the direction of the length of the resilient means and permits of a 35 long and free flexing action of said resilient means in this direction during use. The conventional rigid backing supports for the edge spring member of prior art resilient type lens holding means of this nature have been omitted and have 40 been replaced by the resilient backing sections 9 and 10 so as to provide a wider range of flexibility. The narrowing of the base of the bifurcation also increases the normal pivotal movement of the lens holding means on the lens thereby allowing 45 more flexing action of the resilient means. 50

The upper and lower edges 13 and 14 of the base of the bifurcation and the free ends 15, 16 and 17 of the resilient sections are preferably formed relatively straight transversely thereof so 55 as to provide substantial line contact with each other and with the edge of the lens when the lens holding means is moved about the lens connecting means 7. The line contact of the resilient sections with each other and with the upper and lower edges of the bifurcated member obviates any tendency of the said resilient sections to twist about the connecting means or pin 12 during use, as the pressure of one resilient member on the other is along a transverse line and has 60 no tendency to cause the said resilient members to twist sidewise relative to each other as would be the case if a point contact were provided between said resilient means especially if the contact was to one side of the longitudinal axis of 65 said resilient means. This line contact relation therefore provides smoother acting resilient means which will have no tendency to move out of aligned or stacked relation with each other during the flexing. 70

The pin member or connecting means 12, as shown in Figs. IV and V, is preferably formed rectangular and is adapted to be fitted within aligned rectangular openings formed in the superimposed resilient sections 9, 10 and 11. The pin 75

is provided with a reduced projection 18 adjacent one end thereof adapted to be secured by solder or other suitable means in an opening formed in the body portion 2 of the lens strap. Adjacent 5 its opposite end it is provided with spaced projections 19 which are adapted to be pressed to lie within beveled transverse edges 20 formed in the resilient section 11. During the pressing operation, the pin member 12 is compressed, forcing 10 the body portion thereof into rigid engagement with the side walls of the rectangular openings in the superimposed resilient members, rigidly securing them to the body portion 2 of the lens strap and eliminating all looseness and play in 15 the connection. The purpose of providing a rectangular pin 12, the greater width of which extends in the direction of the longitudinal axis of the superimposed sections, is to provide means whereby the width of the side portions 21 of the 20 various resilient sections on the opposite sides of the connecting means 12 will not be so reduced as to cause them to be weakened to a degree wherein they will not provide a positive and permanent connection and permit the various 25 resilient sections to function properly. The rectangular shaped pin 12 provides a longer bearing surface in a direction longitudinally of the resilient sections and thereby obviates any tendency of the resilient means being displaced sidewise 30 out of relation with each other during use.

The portions 19 pressed into engagement with the beveled end walls 20 provide means for anchoring the resilient means in the direction of flexing and thereby provide a positive and durable attachment. This method of attaching the resilient means to the body portion of the lens holding means enables the spaced lens face engaging portions 4 to be adjusted to any desired spaced relation with each other, independently of 40 the resilient means, to be fitted to lenses of varying thicknesses without danger of having the resilient sections move out of aligned relation with each other as would be the case if a round pin were used and the inner walls of the spaced face engaging portions 4 were depended upon to hold the resilient sections in alignment. It is quite 45 obvious that with the latter structure, if the space between the lens face engaging portions were increased, as happens when the lens holding means is fitted to a thick lens, the inner walls of said face engaging portions would move away from the side edges of the resilient means with a result that the said resilient means would be free to 50 twist about the connecting means out of aligned 55 relation with each other during use.

The various resilient sections 9, 10 and 11 are curved during the forming thereof so as to engage the edge of the lens only adjacent their ends with the central portions thereof adapted 60 to be held in spaced relation with the lens. During the securing of the various resilient sections to the body portion 2, some difficulty was encountered in having the sections become straightened to such an extent that they would not properly fit the edge of the lens. To overcome this 65 tendency of the resilient members to straighten during the attachment thereof to the body portion 2, the said body portion is cupped at its attaching face 22 in the direction of the longitudinal axis of the resilient means to a curvature whose radius is less than the radius of curvature of the edge of the lens at said location but substantially equal to the curvature desired of the resilient means. It is quite obvious that when 70 the projections 19 are pressed outwardly and

rearwardly into engagement with the beveled recesses 20, the cupped face 22 forms backing means for the resilient means and prevents their straightening as would be the case if said face were flat or of a curvature greater in radius than 5 the curvature desired of the resilient means. With this construction there will be more of a tendency to cause the resilient sections, if not already cupped to the curvature of the attaching face 22, to assume this curvature. This is 10 brought about by the fact that the ends 19 of the attaching pin 12 lie within the outer limits of the edges 13 and 14 of the body portion 2 causing the pressure of the attaching operation to be concentrated within these limits and forcing the resilient means inwardly a given amount relative 15 to a plane touching both of said edges 13 and 14.

In Figures VI and VII, there is shown a modified form of the invention wherein the ends 23 of the resilient means 24 nearest the edge of the lens are provided with cylindrical shaped surfaces contacting the edge of the lens. These cylindrical shaped ends function in a manner similar to the ends 17 of the resilient means 11 of Fig. II, only in this instance, instead of having 25 a relatively sharp line contact transversely of the edge of the lens it has a curved face providing a line contact transversely of the edge of the lens, which edge in the plane of the lens, is free to rock as the lens holding means is moved about its 30 point of attachment to the lens. In this instance, the body portion of the lens holding means is beveled rearwardly as indicated at 25 and 26 from points adjacent the opposite sides of the pin member 27 so as to provide a wider range of 35 flexing of the resilient means. In this instance, the resilient section 28 forming the backing means for the resilient section 29 is preferably cupped, as shown in Fig. VIII, in a direction transversely of its longitudinal axis to increase 40 the rigidity of said resilient section. The object of this cupping is to provide means which during the securing of the various resilient sections to the body portion of the lens holding means by the pin member 27 is adapted to prevent a possible 45 straightening of said resilient means. Although the section 28 tends to prevent the straightening of the resilient sections 24 and 29 during the assembling operation with the lens holding means, it provides resilient backing 50 means for said sections, which when in secured relation with the lens holding means permits of a wider range of resiliency.

It is apparent that although the resilient section 24 is shown and described as being provided 55 with upcurved ends 23 the said ends may be so shaped as to have substantial surface contact with the edge of the lens, that is, the said ends may be so formed as to have a substantial portion thereof in intimate surface contact with 60 the edge of the lens. This arrangement would provide means for distributing possible strain which might be introduced at said locations during the flexing of the resilient means over a greater area thereby providing a more positive 65 cushioning effect. It is apparent, however, that the line contact set forth in connection with the structure shown in Fig. II as compared with the prior art point contact of the resilient means 70 with the edge of the lens will greatly relieve the pressure strain at said ends. This in itself greatly reduces the tendency of the lenses to become broken due to strain of this nature during use.

It is apparent that the spring sections 28 and 29 may also be provided with upcurved ends if desired.

It will be noted that the distance between the 5 respective ends 15, 16 and 17 of the various resilient sections and the distance from the edges 13 and 14 from the respective ends 15 of the section 9 are all substantially equal. This is to provide staggered line contact supporting ends 10 or edges at equally spaced intervals intermediate the ends of the resilient section 11 which during the flexing of said section will be successively brought into action to stabilize the flexing of said section throughout its length. The sections 15 9 and 10 resiliently ease off the flexing of the section 11 and increase its tendency to return to its initial set after such easing off. This function takes place in either direction of the flexing; in one direction the upper sections perform the 20 function and in the other direction the lower sections perform the function.

It will be noted that the distance between the ends of the various resilient sections 24, 28 and 29 and the distance between the upper and lower 25 contacting edges 30 and 31 of the lens holding means with respect to the ends of the section 28 are substantially equal and tend to stabilize the flexing of the section 24 in a manner similar to the structure shown in Fig. III.

30 In Fig. IX there is shown another modified form of the invention wherein the resilient sections 32, 33 and 34 are connected to the overlying portion 35 of the lens holding means by spot welding, as indicated at 36. In this instance the 35 pin 12 is not used and the resilient sections are not perforated such as is the case when the pin type connecting means is used. It is obvious that the spot welding method may be used in any of the various structures shown. The spot 40 welding is accomplished by the provision of a suitable apparatus of the conventional type having a contact engaging the springs in the vicinity wherein the welding operation is to be performed. This integrally joins the sections with 45 each other and with the overlying portion 35 at the point 36. Care is taken that the spring sections and the lens holding means are in proper relation before the welding operation is performed.

50 The connecting means 1 may be of the prior art solder connected pivoted type by which a controlled pivotal action may be obtained and more or less permanently maintained during the use of the device. This type of pivotal connection in combination with the resilient means enables the forming of a free acting integral pivotal connection which is limited in its pivotal movement in both directions by the resilient shock and strain absorbing means.

60 From the foregoing description it will be seen that I have provided simple, efficient and economical means and methods of obtaining all of the objects and advantages of the invention.

Having described my invention, I claim:

65 1. In a device of the character described for attachment to a lens, said attachment having a portion adapted to overlie the edge of the lens and a lens connecting portion adapted to engage a face of the lens, said portion overlying the edge 70 of the lens being relatively narrow in a direction following said edge and being provided with a surface which is curved in said direction to a radius which is less than the radius of curvature of the adjacent edge of the lens, a plurality of 75 curved resilient members of varying lengths hav-

ing aligned slots therein extending in the direction of the length of the resilient members and means fitting and extending through the slots and being headed over to overlie and secure the resilient members to the curved surface intermediate the upper and lower edges thereof with the adjacent resilient member curved substantially to the curve of said surface whereby the resilient member which is to engage the edge of the lens will be adapted to engage said edge at 10 two spaced points at a substantial distance to each side of the portion overlying the edge of the lens and will be free to flex throughout the greater portion of its length during use, the means for securing said resilient members to the curved 15 surface being adapted to maintain the said resilient members in surface contact with each other and with the curved surface adjacent the securing means and to urge the resilient members to cup to the curvature of said surface dur- 20 ing use.

2. In a device of the character described for attachment to a lens, said attachment having a portion adapted to overlie the edge of the lens and a lens connecting portion adapted to engage 25 a face of the lens, resilient means having an attaching opening intermediate its sides and the ends thereof which is greater in length in the direction of the longitudinal axis of said resilient means than in its width and means, also elongated in said direction, and shaped to fit and extend into said opening for securing the resilient means to the portion overlying the edge of the lens, said securing means having portions adjacent its opposed ends, only lying in the direction of the longitudinal axis of said resilient means, turned to overlie the adjacent edges of 35 said resilient means on the side thereof which is adapted to be placed nearest the lens.

3. In a device of the character described for 40 use in combination with a lens having a connecting opening therein comprising a portion adapted to overlie the edge of the lens and a portion adapted to overlie a face of the lens and be connected to the lens by securing means fitted in the 45 opening therein and a plurality of resilient members of varying lengths secured intermediate their ends to said portion overlying the edge of the lens substantially intermediate the upper and lower edges of said portion, said portion overlying the edge of the lens being relatively narrow and having a concaved surface in a direction following the edge of said lens and of a radius less than the radius of the adjacent edge of the lens and having spaced relatively straight upper and 50 lower edges extending transversely of the resilient means and providing substantially line contact with the adjacent resilient means when the attachment is moved on the lens about the lens securing means as a center, the length of said 55 portion overlying the edge of the lens being substantially equal to its width and such as to allow the resilient member adapted to engage the edge of the lens to flex substantially throughout the major portion thereof during use.

4. In a device of the character described for 60 use in combination with a lens having a connecting opening therein, comprising a portion to overlie the edge of the lens and a portion adapted to overlie a face of the lens and be connected to 65 said lens by securing means in the opening therein, a plurality of resilient members of varying lengths secured intermediate their ends to a portion overlying the edge of the lens substantially intermediate the upper and lower edges of 70 75 75

5 said portion and in surface contact with said portion, said portion overlying the edge of the lens being relatively short in a direction following said edge and having spaced relatively straight upper and lower edges extending transversely of the resilient means and providing substantially line contact with the adjacent resilient means when the device is moved on the lens about the lens securing means as a center, said resilient 10 members having relatively straight transversely extending end portions providing substantially line contact with each other and with the edge of the lens during said movement, said various line contacts being spaced substantially equal relative 15 to each other in a direction longitudinally of the resilient means, and said portion overlying the edge of the lens being of a length substantially equal to its width and such as to permit the resilient member which is adapted to engage the 20 edge of the lens to flex substantially throughout the major portion of the length thereof.

5. In a device of the character described for use in combination with a lens having a connecting opening therein comprising a portion adapted to 25 overlie the edge of the lens and a portion adapted to overlie a face of the lens and be connected to the lens by securing means fitted in the opening therein and a plurality of continuously curved resilient members secured intermediate their 30 ends to said portion overlying the edge of the lens by a headed pin member which holds the resilient members in surface contact with each other and with the portion overlying the edge of the lens adjacent the securing means, and intermediate the upper and lower edges of said portion, said portion overlying the edge of the lens being 35 relatively narrow in a direction following the edge of said lens and having spaced relatively straight upper and lower edges extending transversely of the resilient means and providing substantially line contact with the adjacent resilient means when the attachment is moved on the lens about the lens securing means as a center, the length of said portion overlying the edge of the lens being substantially equal to its width and such as to allow the resilient member adapted 40 to engage the edge of the lens to flex substantially throughout the major portion thereof during use.

6. In a device of the character described for 45 attachment to a lens, said attachment having a portion adapted to overlie the edge of the lens and a lens connecting portion adapted to engage a face of the lens, said portion overlying the edge of the lens being relatively narrow in a direction which is to follow said edge and being provided 50 with a surface which is cupped in said direction, curved resilient means having a slot therein extending in the direction of the length of said resilient means and means fitting and extending 55 through the slot and being headed over to overlie and secure the resilient means to the cupped surface intermediate the upper and lower edges thereof with the resilient means cupped substantially to the shape of the cupped surface whereby 60 the resilient means will be adapted to engage the edge of a lens at two spaced points at a substantial distance to each side of the portion overlying the edge of the lens and will be free to flex 65 throughout the greater portion of its length during use, the means for securing said resilient means to the cupped surface being adapted to urge and maintain the resilient means in surface contact with said surface.

7. In a device of the character described for attachment to a lens, said attachment having a 70

portion adapted to overlie the edge of the lens and a lens connecting portion adapted to engage a face of the lens, resilient means, and means for securing said resilient means to said portion overlying the edge of the lens, said portion which is 5 adapted to overlie the edge of the lens being relatively narrow in a direction following said edge and having spaced relatively straight edges extending transversely of the resilient means and having a surface which is cupped only in the 10 direction which is to follow the edge of the lens, on which the resilient means are held by said means for securing said resilient means to said cupped surface, said securing means being located intermediate said spaced relatively straight edges 15 and being adapted to urge and maintain said resilient means in cupped surface contact with the cupped surface of said overlying edge portion.

8. In a device of the character described for attachment to a lens, said attachment having a 20 portion adapted to overlie the edge of the lens and a lens connecting portion adapted to engage a face of the lens, resilient means having an opening therein, and rectangular pin-like means for securing said resilient means to said portion overlying the edge of the lens, said securing means extending through the opening in said resilient means and being headed over only on the opposed sides thereof lying in the direction of the longitudinal axis of the resilient means so as to 25 overlie said resilient means only on said opposed sides.

9. The method of forming a lens attachment comprising forming a member having a portion adapted to overlie the edge of the lens and a 30 portion adapted to overlie a face of the lens, providing said portion adapted to overlie the edge of the lens with a surface cupped in the direction which is to lie in a direction following the edge of the lens, providing said surface with a projection, placing resilient means having an opening therein on said projection, and deflecting 35 opposed portions of said projection lying in the direction of the longitudinal axis of the resilient means so as to overlie said resilient means 40 only in said direction and so as to urge said resilient means to the shape of said cupped surface and to retain the same in substantially intimate contact with said surface.

10. The method of securing together the separable parts of an ophthalmic mounting, comprising forming a member having a portion adapted to overlie the edge of a lens and a portion adapted to overlie a face of said lens, providing said portion adapted to overlie the edge 50 of the lens with a surface cupped in the direction which is to lie in a direction following the edge of the lens, providing said surface with a projection, placing resilient means having an opening therein on said projection, and deflecting 55 opposed portions of said projection lying in the direction of the longitudinal axis of the resilient means so as to overlie said resilient means only in said direction and so as to urge said resilient means to the shape of said cupped surface and to retain the same in substantially intimate contact with said surface, placing said member on a lens with the resilient means engaging 60 the edge of said lens and a portion thereof overlying a face of said lens and securing said portion of said member overlying the face of the lens to said lens.

11. In an ophthalmic mounting, a lens, a lens holding member having a portion overlying the 75

- edge of the lens and a lens connecting portion engaging a face of the lens, said portion overlying the edge of the lens being relatively narrow in a direction following said edge and being 5 provided with a surface which is curved in said direction to a radius which is less than the radius of curvature of the adjacent edge of the lens, a plurality of curved resilient members of varying lengths having aligned slots therein extending in 10 the direction of the length of the resilient members and means fitting and extending through the slots and being headed over to overlie and secure the resilient means to the curved surface intermediate the upper and lower edges thereof 15 16 with the adjacent resilient member curved substantially to the curve of said surface whereby the resilient member which is to engage the edge of the lens will be adapted to engage said edge at two spaced points at a substantial distance 20 21 to each side of the portion overlying the edge of the lens and will be free to flex throughout the greater portion of its length during use, the means for securing said resilient members to the curved surface being adapted to maintain the 25 said resilient members in substantial surface contact with each other and with the curved surface adjacent the securing means and to urge the resilient members to cup substantially to the curvature of said surface during use. 30 17. In an ophthalmic mounting, a lens having a connecting opening therein, a lens holding member having a portion overlying the edge of the lens and a portion overlying a face of the lens and connected to the lens by securing means 35 fitted in the opening therein, and having a plurality of resilient members of varying lengths secured intermediate their ends to said portion overlying the edge of the lens substantially intermediate the upper and lower edges of said portion, said portion overlying the edge of the lens being relatively narrow and having a concave surface in a direction following the edge of said lens and of a radius less than the radius of the adjacent edge of the lens and having spaced relatively straight upper and lower edges extending 40 45 transversely of the resilient means and providing substantial line contact with the adjacent resilient means when the lens holding member is

moved on the lens about the lens securing means as a center, the length of said portion overlying the edge of the lens being substantially equal to its width and such as to allow the resilient member engaging the edge of the lens to flex substantially throughout the major portion thereof during use. 5

13. In an ophthalmic mounting, a lens having a connecting opening therein, a lens holding member having a portion overlying the edge of the lens and a portion overlying the face of the lens and connected to said lens by securing means fitted in the opening therein and a plurality of continuously curved resilient members secured intermediate their ends to said portion overlying 15 the edge of the lens and intermediate the upper and lower edges of said portion by a headed pin member which holds the resilient members in substantially surface contact with each other and with the portion overlying the edge of the lens 20 adjacent the securing means, said portion overlying the edge of the lens being relatively narrow in a direction following the edge of said lens and having spaced relatively straight upper and lower edges extending transversely of the resilient 25 means and providing substantially line contact with the adjacent resilient means when the lens holding member is moved on the lens about the securing means as a center, the length of said portion overlying the edge of the lens being substantially equal to its width and such as to allow 30 the resilient member engaging the edge of the lens to flex substantially throughout the major portion thereof during use. 35

14. In an ophthalmic mounting, a lens, a lens holding member having a portion overlying the edge of the lens and a portion overlying a face of the lens and connected thereto, resilient means having an opening therein, and rectangular pin like means for securing said resilient means to 40 said portion overlying the edge of the lens, said securing means extending through the opening in said resilient means and being headed over only on the opposed sides thereof lying in the direction of the longitudinal axis of the resilient means 45 so as to overlie said resilient means only on said opposed sides.

EDWARD M. SPLAINE.
